UNITED STATES PATENT OFFICE.

HENRIK HILLBOM, OF WALLINGFORD, CONNECTICUT, ASSIGNOR TO R. WALLACE & SONS MANUFACTURING COMPANY, OF WALLINGFORD, CONNECTICUT, A CORPORATION OF CONNECTICUT.

DESIGN FOR A SPOON, FORK, OR SIMILAR ARTICLE.

45,716.

Specification for Design.

Patented May 5, 1914.

Application filed June 18, 1913. Serial No. 774,478. Term of patent 7 years.

To all whom it may concern:

Be it known that I, HENRIK HILLBOM, a citizen of the United States, residing at Wallingford, New Haven county, and State of Connecticut, have invented a new, original, and ornamental Design for a Spoon, Fork, or Similar Article, of which the following is a specification, reference being had to the accompanying drawings, forming part thereof.

In the drawings: Figure 1 is a representation of a spoon embodying my novel design, with the outline of a fork indicated by

dotted lines, the obverse side of the design being shown. Fig. 2 is a similar view of the reverse side of the spoon. Fig. 3 is a relatively enlarged view of the outer end of the handle, the severed portion being shown in section.

I claim:

The ornamental design for a spoon, fork or similar article as shown.

HENRIK HILLBOM.
